UNITED STATES PATENT OFFICE

CHARLES J. MULLER, OF EAGLE ROCK, CALIFORNIA

SAFETY CASING VALVE

Application filed January 19, 1929. Serial No. 333,555.

The present invention relates to a safety casing valve and has for its prime object to provide a structure of this nature whereby the valve may be closed with the tools in or 5 out of the well casing in case of a fire, gazer or gusher.

Another very important object of the invention resides in the provision of a casing valve of this nature which is easy to operate, 10 simple in construction, strong and durable, comparatively inexpensive to manufacture, thoroughly efficient and reliable in operation, and otherwise well adapted to the purpose for which it is designed.

15 With the above and numerous other objects in view as will appear as the description proceeds, the invention resides in certain novel features of construction, and in the combination and arrangement of parts 20 as will be hereinafter more fully described and claimed.

In the drawing:

Figure 1 is a top plan view of the valve embodying the features of my invention,

25 Figure 2 is a side elevation thereof,

Figure 3 is a sectional view taken substantially on the line 3—3 of Figure 2,

Figure 4 is a vertical section taken substantially on the line 4—4 of Figure 3,

30 Figure 5 is a vertical section taken substantially on the line 5—5 of Figure 3,

Figure 6 is an enlarged detail section showing the valve closed,

Figure 7 is a perspective view of the Babbitt metal collar, and

35 Figure 8 is a perspective view of one of the valve plates.

Referring to the drawings in detail it will be seen that letter A denotes the upper 40 casting and letter B the lower casting. The upper casting A includes a cylindrical portion 5 for threadedly receiving tubing 6 and rising from a plate 7 integral therewith.

The casting B comprises a cylindrical portion 8 depending from a plate 9 integral therewith and bolted as at 10 to the plate 7. The plate 9 is provided with a pair of oppositely disposed recesses 11 for slidably receiving valve plates 12 and 14 which are of 50 a substantially semi-circular formation and

on the straight edge of the valve plate 12 there is formed a single rib 15 while on the straight edge of the plate 14 there is formed a pair of spaced parallel coextensive ribs 16 for receiving the rib 15 therebetween as 55 will be brought out later.

The edges of these ribs are provided with notches 17. From the same side of the valve plates there extends lug 18. A shaft 19 is journaled through a bushing 20 in the plate 9 and a cap nut 21 is threaded on the bushing to form a stuffing box about the shaft to the outside of the casting 9.

This shaft has oppositely threaded portions 22 threaded in the lugs 18 so that when the shaft is turned in one direction the plates are drawn toward each other and when the shaft is turned in the other direction the plates are moved away from each other.

A frangible Babbitt metal collar 25 has 70 a plurality of grooves 26 cut therein and is provided with ears 27 projecting outwardly at diametrically opposite points to fit into the notches 17 of the ribs 15 and 16. This collar is located between adjacent ends of 75 the cylindrical portions 5 and 8 which are formed with seats 28 and 29 respectively for receiving the upper and lower ends respectively of the collar. The collar 25 provides a smooth, unbroken passage for the 80 fluid through the valve and normally protects the plates 12 and 14 and the screw shaft 19 from the fluid.

A hollow branch 30 projects from the 85 cylindrical portion 8 so that piping 31 may be connected therewith.

The valve is open during all drilling operations as is disclosed in Figures 4 and 5 to advantage. This valve is closed only in 90 case of emergencies. To close the valve it is turned to the right or clockwise by a hand wheel 32 on the shaft 19 and causes the valve plates to move toward each other breaking the Babbitt collar and closing 95 about the tools or cables. If no tool or cable is in the well, then the rib 15 will be received between the ribs 16 to fully close the passage between the castings. An extension 14' is provided on the shaft 19 so that 100

the shaft 19 may be rotated at a remote point from the well.

5 A side outlet or branch is provided at the lower casting to be used as a by path to which the pipe line 31 is connected and leads to any plate remote from the well.

10 It is thought that the construction, operation, utility and advantages of this invention will now be quite apparent to those skilled in this art without a more detailed description thereof.

15 The present embodiment of the invention has been disclosed in considerable detail merely for the purposes of exemplification since in actual practice it attains the features of advantage enumerated as desirable in the statement of the invention and the above description.

20 It will be apparent that changes in the details of construction, and without departing from the spirit or scope of the invention as hereinafter claimed or sacrificing any of its advantages.

25 Having thus described my invention, what I claim as new is:

30 A safety casing valve comprising a sectional pipe fitting composed of a pair of laterally disposed and relatively connected plates having flattened contacting faces centrally apertured and respectively provided with a threaded cylindrical pipe coupling extension aligned with said central apertures of the said plates, one of the said plates having its contacting face recessed on opposite sides of the central aperture, and both of said plates having their contacting faces provided with circular recesses adjacent the edges of the central apertures to provide annular seats, a frangible collar interposed between the contacting faces of the plate with its opposite edges engaged in the said annular seats to provide, in conjunction with the central apertures and extensions of the plate, a continuous bore or passageway 45 through the said fittings, a valve plate in each recess of the said lower plate presenting a straight edge at its inner or collar engaging end, and means for moving the plates toward each other for breaking the 50 said collar and meeting at their inner ends to close said passage.

In testimony whereof I affix my signature.

CHARLES J. MULLER.
